UNITED STATES PATENT OFFICE.

WILLIAM B. VAN VALIN, OF LOS ANGELES, CALIFORNIA.

DESIGN FOR A DOLL.

61,179.

Specification for Design.

Patented July 4, 1922.

Application filed February 10, 1922. Serial No. 635. Term of patent 14 years.

To all whom it may concern:

Be it known that I, WILLIAM B. VAN VALIN, a citizen of the United States, residing at Los Angeles, in the county of Los Angeles and State of California, have invented a new, original, and ornamental Design for Dolls, of which the following is a specification, reference being had to the accompanying drawing, forming part thereof.

In the drawing,
I claim:
The ornamental design for a doll, as shown.

WILLIAM B. VAN VALIN.
